UNITED STATES PATENT OFFICE.

GILBERT L. CROWELL, JR., OF ARLINGTON, NEW JERSEY, ASSIGNOR TO DOMINICK & HAFF, OF NEW YORK, N. Y.

DESIGN FOR A SPOON, &c.

SPECIFICATION forming part of Design No. 23,984, dated February 5, 1895.

Application filed July 23, 1894. Serial No. 518,398. Term of patent 14 years.

To all whom it may concern:

Be it known that I, GILBERT L. CROWELL, Jr., a citizen of the United States, residing at Arlington, in the county of Hudson and State 5 of New Jersey, have invented and produced a new and useful Design for Handles for Spoons, Forks, and Similar Articles, of which the following is a description, reference being had to the accompanying drawings, which 10 illustrate the design.

Figure 1 is a plan or elevation view of the front or obverse side of a spoon, the handle of which embodies my design, the dotted lines showing how the handle may be applied to a 15 fork. Fig. 2 is a similar view of the reverse or rear side of the spoon and handle. Fig. 3 is a cross-section on the plane $a-a$ of Fig. 1.

The general outline of the handle is of the pandurate or fiddle-shape order. Along the 20 edges of the spoon and on both the front and rear sides thereof is located the raised bead-like border A, consisting of a series or row of substantially spherical beads, arranged side by side and touching one another, which beads 25 project above the surface of the main body of the handle whether viewed from the front or the back side thereof, and the outer semi-

circumferences of which constitute the profile or extreme edge line of the handle. At the lower end of the handle, and on both faces of 30 the same is located a raised, conventionalized shell-figure B; and, similarly, upon the upper or front face of the handle appears the lotus figures C, while at the heel of the shank of the handle upon the under side of the same 35 is the shell figure D.

The essential features of this design, whether of the front face or the rear face of the handle, consist of a handle for a spoon, fork, or similar article having a pandurate or 40 fiddle-shaped outline form, and of a row or string of beads running along the entire extent of the outline edge of the handle, the outer edges of the beads constituting the profile line of the handle. 45

What is claimed as new is—

The design for the handle of a spoon, fork or other similar article, substantially as shown and described.

GILBERT L. CROWELL, JR.
